UNITED STATES PATENT OFFICE

102,338

DESIGN FOR A COMBINED BRACELET AND HANDKERCHIEF

David E. Schwab, New York, N. Y.

Application July 17, 1936, Serial No. 63,899

Term of patent 3½ years

To all whom it may concern:

Be it known that I, David E. Schwab, a citizen of the United States of America, residing in the city of New York, county of New York, and State of New York, have invented a new, original, and ornamental Design for a Combined Bracelet and Handkerchief, of which the following is a specification, reference being had to the accompanying drawing, forming part thereof.

Fig. 1 is a plan view of a combined bracelet and handkerchief showing my new design.

Fig. 2 is a perspective view of the combined

bracelet and handkerchief shown in Fig. 1, showing on a larger scale the handkerchief in folded position.

The characteristic feature resides in the jeweled bracelet permanently attached to the center of the handkerchief as shown.

I claim:

The ornamental design for a combined bracelet and handkerchief substantially as shown and described.

DAVID E. SCHWAB.
